CLAIM

The ornamental design for a recess for a golf ball marker, as shown and described.

DESCRIPTION

FIG. 1 is a perspective view showing my new design; FIG. 2 is a top plan view thereof;

FIG. 3 is a left elevational view thereof;

FIG. 4 is a right elevational view thereof;

FIG. 5 is an end elevational view thereof; and,

FIG. 6 is an opposite end elevational view thereof.

The broken lines in the drawings illustrate environmental structure and form no part of the claimed design.

1 Claim, 4 Drawing Sheets(56)
